H. G. GILLMOR,
RAIL ANCHOR,
APPLICATION FILED SEPT. 17, 1915.

1,224,113.

Patented Apr. 24, 1917.

UNITED STATES PATENT OFFICE.

HORATIO G. GILLMOR, OF WASHINGTON, DISTRICT OF COLUMBIA.

RAIL-ANCHOR.

1,224,113.

Specification of Letters Patent. Patented Apr. 24, 1917.

Application filed September 17, 1915. Serial No. 51,203.

To all whom it may concern:

Be it known that I, HORATIO G. GILLMOR, a citizen of the United States, residing at Washington, in the District of Columbia, 5 have invented a new and useful Rail-Anchor, of which the following is a specification.

This invention relates to devices known as rail anchors, rail stays or anticreepers and 10 one of its objects is to provide a simple device which will prevent the longitudinal movement of the rails of railways.

Other objects are to provide for the use of the device upon rails of more than one size 15 without change in the device and to provide for the proper fitting of the device upon rails which may be either larger or smaller than the rail for which the device may be specially intended.

20 To the accomplishment of these objects and such others as may hereinafter appear, as will be readily understood by those skilled in the art, the invention comprises a rail anchor embodying the features of construction, the combination of elements and the arrangement of parts having the general mode of operation as hereinafter described and claimed.

The preferred embodiment of the invention 30 is shown in the accompanying drawings, in which:—

Figure 1 is a side view partially in section illustrating the application of the device to a rail of standard size; Fig. 2 is a 35 side view partially in section illustrating the application of the same device to a rail smaller than the standard size; Fig. 3 is a plan view of the top of the base engaging transverse element; and Fig. 4 a plan view 40 of the bottom of this transverse base engaging element. Fig. 5 is a side view partially in section illustrating the application of the device to a rail larger than the standard size and Fig. 6 is a detail view partially 45 in section illustrating a position of the two parts when applying the device to a rail larger in size than the standard rail.

Similar letters refer to similar parts throughout the several views.

50 In the form of the invention illustrated in the drawings, A represents the rail resting upon ties or sleepers, a portion of one of which is shown at B in Fig. 1. The rail an-

chor comprises a base flange gripping member C and a vertical pressure producing or 55 clamping member D. The base flange gripping member is formed with a portion E engaging the upper surface of the base flange of the rail and spaced portions F lying below and in spaced relation to E, engaging the bottom of the rail base. The member C has stops G presenting relatively small contact surfaces arranged to engage the edge of the rail base, as illustrated in Figs. 1 and 2, under certain conditions; and 60 surfaces H, which under certain conditions such as illustrated in Fig. 5, come into contact with the edge of the rail base. The member C is provided with a plurality of seats I and K either of which may engage 65 with the member D. One or both of these seats may be grooved as at L and each of the seats may present both convex and concave surfaces for successive engagement with the member D. A concave surface of one of 70 the seats is shown at M in Fig. 2 and another at N in Figs. 5 and 6. The member D is constructed to engage either of the seats in the member C and to engage the surfaces of these seats in succession as it moves angularly in being forced into position. The member D has an arm O arranged to engage 75 the upper surface of the base flange of the rail base at the side of the rail opposite to E and to grip or clamp the rail between this arm O and the member C. The arm O may have surfaces P lying out of the plane of the surfaces Q and R of this arm.

The device is applied to the rail by placing the member C transverse to the rail with 80 the arm E engaging the top of the base flange of the rail at one side of the rail and the surfaces F engaging the bottom of the base flange of the rail. The member C is then forced into position by striking it at 85 T with a hammer or maul to drive it transversely to the rail. If the rail be of standard size the member C will be in correct position when it has been driven transverse to the rail until the edge of the base of the rail 90 contacts with the stops G, and in this position the member D may be placed with its surface U engaging the surface N or the member C and the surface Q of the arm O 95 will be brought into contact with the rail 100 base as illustrated in Fig. 6. The member D

is then forced into position by striking upwardly directed blows at the portion V of the member D and in being forced into position it will move angularly about first the 5 surface N and then the surface L. The convexity at P of the arm O of the member D permits the angular movement necessary in the member D to be effected more readily than would otherwise be the case and facilitates the driving of this member into place. The driving of the member D continues to produce angular movement in D until the final position shown in Fig. 1 is reached. With the parts in this position the member 10 C is gripping the rail and the rail is gripped and clamped between the members C and D. If the rail tends to move these parts are carried with the rail until the tie engaging portion W of the member C is brought into 15 contact with the tie B. Thereafter the further movement of the rail is prevented by the engagement of W with the tie B.

Should the rail, to which it is desired to apply the device, be smaller than the standard size of rail for which the device is 20 specially arranged to an extent which would make the fit of the parts C and D with one another such that the member D would be too loose upon the rail base and the rail therefore not effectively gripped between the members C and D, the member D is 25 made to engage with the seat I instead of with the seat K as previously described and is forced into position as described above.

When engaging this seat I the rail will be 30 effectively gripped between the members C and D and properly held against the creeping movement as above described. The position of the parts when fitted one to the other and in place on the rail is illustrated 35 in Fig. 2.

Should the rail to which it is desired to fit the device be larger in size than the standard for the size for which the device is specially 40 adapted the member C is driven by the blows at T beyond the position at which the stops G contact with the edge of the rail base and the stops G are in this way upset or sheared off and deflected to the form 45 shown by X in Figs. 3 and 5. This deformation of the stops G permits the member C to be driven to a position such that the member D may be placed as before described and as illustrated in Fig. 6 ready to be driven 50 into position. When being driven into position the member D engages the seat K which has the recess or groove L and since the rail A is larger than normal the stresses put upon the seat K are greater than would be 55 the case if the rail were of normal size. The groove or recess L permits the seat K to be deformed or upset and the distance of the seat K from the bottom of the rail to be somewhat reduced as the member D is driven 60 into position and in the final position, illus-

trated in Fig. 5, this groove or recess L will be partially or wholly closed.

It will readily be understood that by constructing the parts in the manner illustrated and described a considerable range in 70 the size of rail to which the device may satisfactorily be applied may be provided for.

Obviously some features of the invention may be used without others and the invention may be embodied in widely varying forms, within the skill of the artisan.

Therefore, without limiting the invention to the construction shown and described or enumerating equivalents, I claim and desire to secure by Letters Patent:—

1. A rail gripping part constructed with 80 a stop which may be deformed to permit said part to be driven transversely upon a rail.

2. A rail base flange engaging and gripping part for rail anchors constructed with 85 rail base edge engaging portions adapted to be changed in form to permit said part to be driven transversely upon a rail.

3. A rail engaging and clamping element 90 for anticreepers constructed with a jaw at one end adapted to engage one edge of the rail base and on the under side of the other end a plurality of seats each adapted to engage a rotatable pressure producing part. 95

4. A rail engaging and gripping element constructed with a seat adapted to engage a vertical pressure producing part and arranged to deform to adapt said part to variation in the size of the rail.

5. A rail embracing and gripping part 100 constructed with deformable rail edge engaging portions and a deformable seat adapted to engage with a pressure producing part.

6. A vertical pressure producing part having an arm, adapted to engage the upper surface of the rail base flange, said arm being constructed with a recessed portion arranged to contact with the rail base while 110 said part is being forced into position and to be out of contact with the upper surface of the rail base when said part is in position.

7. A pressure producing part for anticreepers constructed so to engage a transversely applied part as to be movable angularly about said part and provided with a recessed arm adapted to engage with the upper surface of the base flange of a rail. 115

8. A rail anchor comprising a rail gripping element constructed with a deformable rail base edge engaging portion permitting variation in the width of the rail base and a part arranged to grip the rail between said part and said element. 120

9. An anticreeper for rails comprising a transversely disposed rail gripping element constructed with deformable rail edge engaging portions arranged to permit width variations and a horizontal and vertical 125 130

pressure producing element constructed to engage said rail gripping element and the rail.

10. A rail stay comprising a rail engaging part constructed with a plurality of seats each adapted to engage a vertical pressure producing element arranged to adapt said part to fit more than one size of rail and a pressure producing part constructed to engage one of said seats and the upper surface of the rail base and to grip the rail base between said part and element.

11. A rail anchor comprising a transverse rail engaging and gripping element constructed with a deformable seat arranged to engage a pressure producing element and adapt the parts to fit varying sizes of rails and a vertical pressure producing part arranged to engage said deformable seat and the rail base and to grip the rail between said element and said part.

12. An anticreeper for rails comprising a transverse element having a seat upon the under side of one end thereof and a vertical pressure producing part engaging said seat constructed with an arm adapted to engage the upper surface of the rail base flange, said arm being constructed with a recessed portion arranged to contact with the rail base while being forced into position and to be out of contact with the upper surface of the rail base when said part is in position, and means for giving one of said parts a fixed position in the roadbed as against the tendency of the rail to creep.

13. A rail anchor comprising a transversely applied part and a pressure producing part constructed to so engage said transversely applied part as to be movable angularly about said part and provided with a recessed arm adapted to engage with the upper surface of the base flange of the rail.

14. A device for preventing the creeping of rails comprising a transversely applied element having tie engaging means and a pressure producing part constructed so to engage said element as to be rotatable about said element and provided with a recessed arm adapted to engage with the upper surface of the base flange of the rail.

15. An anticreeper for rails comprising a transverse rail engaging and gripping element constructed with a deformable seat arranged to engage a pressure producing part and adapt the device to fit varying sizes of rails and a vertical pressure producing part arranged to engage said deformable seat and the rail base and to grip the rail between said element and said part.

16. A rail anchor comprising a transverse rail engaging and gripping element constructed with a deformable seat and a pressure producing part engaging said deformable seat and having a recessed arm adapted to engage the upper surface of the rail base.

17. A device for preventing the creeping of rails comprising a transverse rail engaging element constructed with a deformable seat and a tie engaging portion and a pressure producing part arranged to engage said deformable seat and provided with an arm adapted to engage the upper surface of the rail base said arm being constructed with a recessed portion arranged to contact with the rail base edge while said part is being forced into position and to be out of contact with the upper surface of the rail base when said part is in position.

18. A rail anchor comprising a transverse rail engaging and gripping element constructed with a deformable seat and a pressure producing part engaging said deformable seat and the rail base to grip the rail between said element and said part and means whereby one of the parts is given a fixed position in the roadbed as against the tendency of the rail to creep.

19. An anticreeper comprising a rail engaging and gripping element constructed with a deformable rail edge engaging portion and a deformable seat and a pressure producing part engaging said deformable seat and the upper surface of the rail base to grip the rail base between said element and said part.

20. A rail anchor comprising a rail engaging and gripping element provided with means for engaging a tie in opposition to the tendency of the rail to creep and constructed with a deformable rail edge engaging portion and a deformable seat and a part engaging said deformable seat and the upper surface of the rail base and gripping the rail between said element and said part.

21. An anticreeper comprising a rail engaging and gripping element constructed with a deformable rail base edge engaging portion and a pressure producing part engaging said element and provided with a recessed arm adapted to engage the upper surface of the rail base to grip the rail base between said element and said part.

22. A rail anchor comprising a rail gripping element having a rail base edge engaging portion which may be changed in shape to adapt said element to rails of varying width, a part engaging said element and provided with an arm adapted to engage the upper surface of the rail base provided with cam surfaces whereby as said part is forced into position the rail base is gripped between said element and said part and means whereby one of the parts engages a tie in opposition to the tendency of the rail to creep.

23. A device for preventing the creeping of rails comprising a rail engaging and gripping element provided with means for engaging a tie and a pressure producing part engaging said element and constructed with an arm having cam surfaces adapted to en-

page the upper surface of the rail base to effect a gripping of the rail base between said element and said part when said part is forced into position.

24. A rail anchor comprising a rail base gripping element constructed with a plurality of seats to adapt said element to more than one size of rail a part engaging one of said seats and the rail base to grip the rail base between said element and said part and means for holding one of said parts in opposition to the tendency of the rail to creep.

25. An anticreeper comprising a rail gripping element having deformable rail base edge engaging portions and a plurality of seats for adapting the element to varying widths of rail base and a part engaging one of said seats and the upper surface of the rail base for gripping the rail base between said element and said part.

26. A rail anchor comprising a rail engaging and gripping element constructed with deformable rail edge engaging portions and a plurality of seats for adapting said element to rails of varying width of base a part engaging one of said seats and the upper surface of the rail base and means for

giving one of the parts a fixed position in the roadbed as against the tendency of the rail to creep.

27. A rail stay comprising a rail gripping element constructed with a rail base edge engaging portion which may be changed in shape and with a plurality of seats and a pressure producing part engaging one of said seats having an arm with cam surfaces adapted to engage the upper surface of the rail base to effect the gripping action as said part is forced into position.

28. A rail anchor comprising a rail engaging and gripping element constructed with a deformable rail base edge engaging portion and a plurality of seats a pressure producing part engaging one of said seats and having a cam arm adapted to engage the upper surface of the rail base for effecting the gripping action of the anchor and means for giving one of the parts a fixed position in the roadbed as against the tendency of the rail to creep.

H. G. GILLMOR.
